UNITED STATES PATENT OFFICE.

HENRY W. JOY, OF NEW YORK, N. Y.

DIAPHRAGM.

Application filed April 21, 1925. Serial No. 24,779.

My invention relates to improvements in diaphragms such as are commonly employed in sound reproducing apparatus.

The principal object of the invention is to provide a diaphragm of this character which may be used in connection with telephones, radio loud speakers, and the like.

A further object of the invention is to provide means to secure vibrations of the diaphragm that will in their entirety synchronize exactly with the highest to the lowest values of the modulated current operating the customary electro-magnet commonly employed to vibrate a diaphragm.

It has been found necessary to increase the resilience or springiness of the diaphragm as commonly used in radio loud speakers and the like, so that the spring recoil of the diaphragm shall have a higher velocity or number of vibrations per second than prevail in all high pitched audible sounds. If the resilience of any diaphragm is of a slower period than the pulsations of the operating or voice carrying current, then the fatigued areas of the diaphragm will lag behind the vibrations set up at and near the center of the diaphragm. The center of the diaphragm by reason of its receiving the greatest impulse from the magnet will respond to the pull or release of the latter, before the concentric regions thereof between the center of the edge have had time to vibrate in harmony with the movement set up at the center.

With the above in mind the present invention comprehends a diaphragm capable of having simultaneous movements over the entire surface, and I accomplish this result by impressing a series of ridges, radiating from the center and preferably diminishing in cross section as they approach the edge. I have found that an odd or even number of ridges may be employed, but the ridges should by preference be equi-distant, the one from the other. Diaphragms according to the present invention may be pressed from metal, glass or any resilient substance, the overall diameter thereof conforming to the requirements of service. It will be clear that the gauge of the diaphragm will vary according to the material used as well as the relative diameter.

In practice I have found it preferably to impress identically formed radiating ridges which approach each other, and a common center, as near as is mechanically possible.

One embodiment of my improved dia-

phragm is illustratively exemplified in the accompanying drawings, in which, Fig. 1 is a plan elevational view of the diaphragm; Fig. 2 is a substantially cross sectional view taken on the line 2-2 of Fig. 1; and Fig. 3 is a transverse sectional view through one of the ribs of the diaphragm.

Referring to the drawings, 10 denotes the diaphragm proper which comprises a disk having a plurality of uniformly spaced radial ridges 11 impressed therein. The diaphragm is supported between annular members 12 and vibrated by means of an electro-magnet 13.

As the actual center of the diaphragm 10 cannot accommodate the inner or meeting ends of the ridges, the center is depressed to form a conically shaped portion 14. The apex of the cone is directed towards the electro-magnet 13 and carries a projection 15, preferably of soft iron, which is disposed within the magnetic field of the electro-magnet 13. It is not absolutely necessary to depress the diaphragm at the center to form a cone shaped portion because any desired shape may be used, the object being to prevent the actual center from vibrating before any other portion of the diaphragm. The conically shaped center 14 is merely suggested in order to strengthen the actual center of the diaphragm which must transmit vibrations to all the ridges in unison, because, as the ridges vibrate so each vibration is transmitted simultaneously to the entire surface of the diaphragm, thus preventing any lag or fatigue.

It will be clear that the travel or oscillations of the diaphragm will be greatest at and near the center, and such oscillations will diminish as the edge of the diaphragm is approached concentrically.

The operation of the diaphragm is as follows:—The center of the diaphragm receives an impulse from the magnet 13. The deflection is then transmitted direct to and without loss of time to all the ridges which in turn carry the flat or plane areas of the diaphragm with them, so as to bring the whole area of the diaphragm into vibration in absolute unison to the magnetic impulse. The ridges 11 by virtue of their shape resist all movement other than a rise and fall in a plane at right angles to the plane of the diaphragm 10.

What I claim is:—

- An acoustical diaphragm of resilient

material having a plurality of impressed ridges radiating from near the centre of the diaphragm towards its periphery, said ridges being of gradually decreasing cross section from the centre toward the periphery of the diaphragm.

2. An acoustical diaphragm of resilient material having a conical depression at its centre and a plurality of equidistantly spaced impressed ridges radiating from the conical

depression to a line short of the periphery of the diaphragm, said ridges being widest at said conical depression and gradually decreasing in cross section to the vanishing point toward the periphery of the dia- 15 phragm.

In testimony whereof I have affixed my signature.

HENRY W. JOY.
